(57) **CLAIM**

The ornamental design for a pool equipment screen panel assembly, as shown and described.

DESCRIPTION

FIG. 1 is a perspective view of an embodiment of the pool equipment screen panel assembly;

FIG. 2 is a front elevation view of the pool equipment screen panel assembly;

FIG. 3 is a rear elevational view of the pool equipment screen panel assembly;

FIG. 4 is a left side elevational view of the pool equipment screen panel assembly;

FIG. 5 is a right side elevational view of the pool equipment screen panel assembly;

FIG. 6 is a top plan view of the pool equipment screen panel assembly;

FIG. 7 is a bottom plan view of the pool equipment screen panel assembly;

FIG. 8 is a perspective view of an additional embodiment of the pool equipment screen panel assembly;

FIG. 9 is a front elevation view of the pool equipment screen panel assembly;

FIG. 10 is a rear elevational view of the pool equipment screen panel assembly;

FIG. 11 is a left side elevational view of the pool equipment screen panel assembly;

FIG. 12 is a right side elevational view of the pool equipment screen panel assembly;

FIG. 13 is a top plan view of the pool equipment screen panel assembly; and,

FIG. 14 is a bottom plan view of the pool equipment screen panel assembly.

Any broken lines shown in FIGS. 1-14 are included for the purpose of illustrating environmental elements only and form no part of the claimed design.

1 Claim, 8 Drawing Sheets
